() Term: 14 Years

(57) CLAIM

(21) Appl. No.: 29/168,068

The ornamental design for "bathtub," as shown.

(22) Filed: Sep. 24, 2002

DESCRIPTION

(30) Foreign Application Priority Data

Apr. 4, 2002 (JP) 2002-009049

FIG. 1 is a front view showing the design of this invention;

(51) LOC (7) Cl. 23-02

FIG. 2 is a back view thereof;

(52) U.S. Cl. D23/277; D23/280.2

FIG. 3 is a right side view thereof;

(58) Field of Search D23/273, 275,

FIG. 4 is a left side view thereof;

D23/276, 277, 278, 279, 280.1, 280.2, 280.3,

FIG. 5 is a top view thereof;

303, 304, 305; D24/204, 205; 4/538, 546-548,

FIG. 6 is a bottom view thereof; and,

551, 555-557, 559, 571.1-579, 584-586,

FIG. 7 is a perspective view thereof.

589, 593, 661
